UNITED STATES PATENT OFFICE.

THOMAS T. ROCKETT, OF PHILADELPHIA, PENNSYLVANIA.

COVER FOR RADIATORS.

SPECIFICATION forming part of Letters Patent No. 403,772, dated July 9, 1889.

Application filed April 2, 1889. Serial No. 305,709. (No model.)

To all whom it may concern:

Be it known that I, THOMAS T. ROCKETT, of Philadelphia, in the county of Philadelphia and State of Pennsylvania, have invented certain new and useful Improvements in Cast-Iron Tops or Covers for Radiators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improved top or hood for hot-air furnace-radiators; and it consists in certain novel features of construction and combinations of parts more fully described hereinafter, and particularly pointed out in the claims.

Referring to the accompanying drawings, Figure 1 is an inverted perspective view of the cast top. Fig. 2 is a top perspective view of the same. Fig. 3 is a vertical central section of a furnace-radiator and the top or hood in position.

Heretofore hot-air furnace-radiators, in some instances, have consisted of an annular chamber formed of sheet metal, having similar annular top and bottom plates secured to and closing the top and bottom of the chamber, the fire-box of the furnace being extended upwardly, and a cylindrical chamber located in the open space of the said annular chamber, with a closed top and its open bottom resting on said extended portion of the fire-box, and a straight passage within said open space of the annular chamber extending from said cylindrical chamber to the annular chamber, said horizontal passage and cylinder being located within the space of the annular chamber and formed of sheet metal, and located in a plane beneath the top plate of the chamber; but this construction is exceedingly difficult and expensive to manufacture. It cannot be cast, but must be made of sheet metal; hence the cost and labor of production are greatly enhanced.

The object of my invention is to so change the construction of the above-mentioned class of radiators that an improved top or hood for the same can be used, which shall be ex-

ceedingly cheap and easy to manufacture and of such form and construction that the entire cap and transverse flue are cast integral; and also to construct this cap so that there shall be an increased radiating-surface as the products of combustion pass up the vertical passage, then across the transverse flue of the hood, and then down into the annular chamber.

On the drawings the reference-letter *a* indicates the vertical passage from the fire-box of a stove or furnace, (not shown,) up which the products of combustion pass. The upper end of this passage is closed by a hemispherical dome or cap *b*, from the side of which a horizontal flue *c* extends radially, as clearly shown. This flue is, preferably, rounded on top and is closed at its outer extremity, while the lower side of its outer portion rests upon the top ring or plate of an annular chamber *e*, and the interiors of said flue and chamber communicate through the opening *d*, and said chamber surrounds the passage *a*, leaving an annular air-heating space *f* between the passage or cylinder *a* and chamber *e*, and the top of said cylinder is in a plane below that of the dome or cap *b* and transverse flue. It will thus be seen that the products of combustion pass up the passage *a* to the cap *b* through the transverse flue and down into the annular chamber, which is provided with a partition *g*, (partially shown in Fig. 3,) whereby the products of combustion are forced to travel around the annular chamber to the exit *h*, leading to the smoke-pipe or chimney, the partition being located between the discharge end of the transverse flue and the exit from the chamber. It will thus be seen that the air passing up within the casting of the furnace (shown in dotted lines in Fig. 3) is heated by passing in contact with the heated surfaces of the parts through which the products of combustion pass. The annular chamber can be provided with another opening *i*, if desired.

The circular chamber can be cast with its top open or formed of sheet metal, as found most desirable, and the top of this chamber is closed by an annular cast-iron ring *j*, provided with flanges, as shown, to hold it in position, and with ears *k* on its inner and outer edges to register with corresponding ears on the sides of the chamber, which ears are

bolted or riveted together. This top or ring, the cap *b*, and the transverse flue *c* are all cast in one piece, as shown, having strengthening-pieces extending from the cap *b* to the 5 ring, and the ring is provided with a transverse opening *d*, (as before mentioned,) by means of which communication between said flue and annular chamber is established. The lower edge of the cap or dome is also provided 10 with a flange to fit the upper end of the passage *a*.

This invention consists in this cap or top and transverse flue cast in one piece, thereby greatly reducing the cost, time, and labor of 15 production and manufacture and producing an improved article and increasing the effectiveness and cheapness of the radiator.

What I claim is—

1. The combination, with the passage conveying the products of combustion from the fire-box of a furnace, and an annular chamber provided with an exit and surrounding the passage, of a dome or cap closing the top of said 20 passage, a ring closing the top of said 25 annular chamber, and a horizontal flue extending radially from said cap and resting upon the top of said ring and opening through the same into said chamber, said ring-flue and cap being cast in one piece separate from said 30 passage and chamber.

2. In a hot-air furnace, the combination,

with a vertical passage for the products of combustion, and an annular radiator-chamber provided with an exit and into which said products of combustion are passed, of a dome 35 or cap closing the top of said chamber, a ring closing the top of said chamber and located in a plane below the cap, and a flue extending radially from said cap to and resting upon the top of said ring, the outer end of the flue 40 being closed and the ring being provided with an opening connecting said chamber and flue, the cap, flue, and ring being cast in one piece, substantially as described.

3. In a hot-air furnace, a vertical passage 45 for the products of combustion, and an annular chamber surrounding the same, into which the products from the passage pass, in combination with a single integral casting forming a cap for the upper end of the passage, a ring forming the top of said chamber, and a flue opening into and extending radially from the cap to an opening through the ring, substantially as described.

In testimony that I claim the foregoing as 55 my own I affix my signature in presence of two witnesses.

THOS. T. ROCKETT.
